[57] CLAIM

The ornamental design for a gas cap for motorcycles, as shown and described.

DESCRIPTION

FIG. 1 is a top plan view of a gas cap for motorcycles showing our new design;

FIG. 2 is a bottom plan view thereof;

FIG. 3 is a front elevational view thereof, the rear being a mirror image of the front shown thereof;

FIG. 4 is a right side elevational view thereof;

FIG. 5 is a left side elevational view thereof;

FIG. 6 is a cross sectional view thereof, taken in directions of the arrows along line 5—5 of FIG. 1;

FIG. 7 is an exploded side elevational view thereof; and,

FIG. 8 is a top perspective view thereof.
